UNITED STATES PATENT OFFICE.

THOMAS A. HUTSELL, OF SPOKANE, WASHINGTON, ASSIGNOR TO HUTSELL MOTOR COMPANY, OF SPOKANE, WASHINGTON.

INTERNAL-COMBUSTION ENGINE.

Application filed July 17, 1920. Serial No. 396,991.

To all whom it may concern:

Be it known that I, THOMAS A. HUTSELL, a citizen of the United States, residing at Spokane, in Spokane County and State of Washington, have invented certain new and useful Improvements in Internal-Combustion Engines, of which the following is a specification.

The present invention relates to improvements in internal combustion engines of the two cycle type in which the working cylinder and pump cylinder are co-axial and the working piston and larger pump piston form a rigid structure. The engines are arranged in pairs, whereby the fuel charge is alternately compressed in one pump cylinder and pumped through a communicating manifold to the adjoining ignition chamber of the parallel working cylinder, above the motor piston therein, thus readily adapting the invention for two, four, six or eight cylinder engines or motors.

The invention consists essentially in certain novel combinations and arrangements of parts including the co-axial working and pump cylinders, which as separate elements, are combined with the engine base and block or casing to secure proper fitting of the parts together for most efficient operation of the engine or engines. The invention also provides improved means for conducting the fuel charges and exhaust gases to and from the cylinders, as will be pointed out, together with lubricating means for the pistons forming part of the crank shaft of the engines, and in further details of construction illustrated in the drawings, and set forth in the appended claims.

In the accompanying drawings I have illustrated a four cylinder engine of well known type embodying the novel features of my invention, wherein the parts are combined and arranged according to the best mode I have thus far devised for the practical application of the principles of my invention.

Figure 1 is a vertical, transverse sectional view through the engine embodying my invention, illustrated as taken at line 1—1 of Figure 2.

Figure 2 is a view in side elevation, with parts in section, of a four cylinder engine

embodiment of my invention, illustrating the manifold connection for fuel charge from one cylinder to an adjoining cylinder, and showing the working or operating parts of the engine, both in section and in elevation.

Figure 3 is a perspective view of the crank shaft with its disks for distributing the oil or lubricant from the oil pan of the engine.

Figure 4 is a view in side elevation of the working cylinder of an engine.

Figure 5 is a view of the combined working piston and pump piston, fashioned as a rigid structure, partly broken away for convenience of illustration.

Figure 6 is a side view of a detached pump or compression cylinder, showing one of its interlocking supporting lugs and a pair of ports for communication with the working cylinder of an adjacent engine for conveying a compressed charge thereto.

In the preferred form of the invention as indicated in the drawings I have utilized a four cylinder engine or motor, arranged in pairs A and B, in which the engine base 1 is of usual form and divided by the central vertical partition 1^a, and below the base is the oil pan 2, while the engine block 3, above the base is fashioned as a rigid structure to form the water jacket 4 for a pair of engine cylinders. Each engine is equipped with a working cylinder 5 and a compression or pump cylinder 6, disposed in axial alignment, or co-axial, but separate elements embodied in the engine structure. The pump cylinder 6, as seen in Figure 6 is a comparatively large cylindrical sleeve fashioned with a pair of diametrically disposed, exterior lugs 7, which as best seen in Figure 1, rest upon the flanges 8 of the engine casing at the top edge of the engine base, to support the working cylinder. Bolts are passed through flanges on the engine block and engine base in usual manner to secure these two parts of the engine, and the working cylinder, in rigid relationship.

The working or motor cylinder 5 is also rigidly supported in the engine, in upright position, and is centered and supported at the top by the utilization of a hollow threaded stud 9, threaded into the cylinder head 10, and provided with a securing nut 10^a outside the cylinder head. The ignition de-

vice or spark plug 10^b is threaded into the interior of the hollow stud 9, for igniting the explosive charge in the firing chamber of the working cylinder 5.

5 The working cylinder is closed at the top, except for the hollow stud 9 and open at the lower end, and approximately midway its center is provided with an exterior, annular boss 11, formed with a lower beveled edge 12, and through the walls of this boss extend the two, diametrically opposed inlet and exhaust ports 13 and 14 for the fuel charge and spent gases respectively.

10 Adjacent these ports of the working cylinder are the complementary inlet and outlet passages 15 and 16 extending radially through the cast integral ring 17 of the engine block or casing 3, which ring is fashioned with an upper, inwardly projecting annular flange 18 to receive the shoulder 19 of the boss 11 on the working cylinder, and a lower shoulder 20 for the flange or beveled face 12 of this exterior boss of the working cylinder. In this manner the working cylinder is rigidly secured within the engine casing where it is supported at the head by the hollow stud 9, and approximately midway its length within the annular casting or ring 17 of the engine casing.

15 25 It will be apparent that the sleeve 6 forming the pump cylinder is of greater internal diameter than the external diameter of the working cylinder which extends approximately one-half its distance within the pump cylinder and forms an annular compression chamber 21 between the inner and outer faces of the cylinders. The carburetor 22 in Figure 1 communicates with the compression chamber 21 through the intake manifold 23, port 24 in the engine casing, and intake port 25 through the pump cylinder wall. Diametrically opposite the intake ports, the compression chamber has outlet ports 26, through the wall of the pump cylinder, and this port opens through the engine casing at 27 to the charge manifold 28. The charge manifolds 28 and 29, thus extend from their respective pump cylinders, are crossed, and lead to the complementary 30 working cylinders of adjoining engines, thence through passages 15 and ports 13 to the interior of the working cylinders 5. In this manner provision is made for taking a fuel supply into the compression chamber 55 on the working stroke of the piston, and for transmission of the compressed charge from this compression chamber, through a charge manifold to the working cylinder of the adjoining engine, the charge being propelled from the compression chamber on the return or upstroke of the piston.

60 In Figure 5 the combined working piston 30 and pump piston 31 are illustrated as a rigid structure, each provided with packing rings 32 of usual type, and designed to re-

ciprocate in the co-axial cylinders 5 and 6. In Figure 1 the connecting rod 33 is pivoted in the lower end of the hollow piston on the wrist pin 34 and journaled on the bearing of the crank shaft 35 in usual manner. The 70 crank shaft is journaled in bearings in the engine base and is preferably an integral member. At the sides of the wrist pin couplings of the several connecting rods with the crank shaft, are provided integral, circular disks 36, concentric with the axial line of the shaft, and arranged in pairs. These transversely arranged disks are of sufficient diameter to extend into the oil pan of the engine base, and to furnish weight to stabilize the shaft and insure correct alignment and true operation of the shaft.

75 Within the engine base and below the crank shaft are provided spaced partitions 37, vertically disposed, and dividing the oil pan into pockets, each to accommodate a pair of disks, and from which the revolving disks, by centrifugal action may pick up oil and spray it up into the lower open ends of the cylinders and the hollow piston. By this action of the oil spraying disks the interior walls of the cylinders are lubricated and the piston stem connections are also supplied with lubricant. Within each of the 80 hollow pistons 30, is provided a flange or shelf 38 forming an annular groove, and from this groove radiate a series of inclined ports extending through the wall of the piston. Thus the lubricant is gathered by the disks below each engine as the disks pass 90 through the oil in the oil compartments or pockets, and by the centrifugal action of the revolving disks, the oil is thrown up into the hollow pistons against the walls above the shelves, and flows back to the groove of 95 the shelf, thence through the ports 39 to lubricate the piston 30 in its cylinder. By the utilization of this lubricating system the necessity for pumps and their accessories 100 is eliminated with a consequent saving in 110 cost of production of the motor and maintenance of the equipment.

115 In Figure 1 it will be observed that the pump piston 31 is a sleeve of sufficient bore to enclose the lower end of the motor piston 30, and form the annular compression chamber or space 21 the upper end of this space being open, and the lower end of the space is closed by the exterior ring or annular flange 40 formed near the lower end of the 120 tube which functions as the motor piston 30.

125 The inwardly extending annular flange 41 at the bottom of the piston 30 fits under the flange 40, and bolts 42 screwed in to these flanges 40 and 41 secure the tubular members to form the rigidly constructed motor and pump pistons 30 and 31.

130 The pump piston 31 is provided with an orifice or port 43 opening outwardly from the compression chamber 11, and adapted to

register with the compression charge port 26, previously described, in the wall of the cylinder 7.

In operation assuming the pistons to be in the upper position indicated in Figures 1 and 2, as the pistons are moved downwardly under impact of the explosion a vacuum is formed in the annular space or chamber 21 as the pump piston recedes in its cylinder 7, until at its lowermost position the pump piston uncovers the port 24 and orifice 25 to admit a fuel charge from the intake manifold to the compression chamber or annular space 21. The quantity of gas thus admitted is governed by the time this inlet port remains open and by the position of the throttle valve in the carburetor 22, and the fuel charge rushes in through the intake port to fill the vacuum in the annular chamber 21. The returning, upward stroke of the rigid pistons causes the intake port to be closed as soon as the upper edge of the pump piston passes over the intake ports 24-25 and the charge thus carried by the pump piston in the annular space and above the upper edge of the rising pump piston, is compressed as the space decreases, until the pump piston reaches the upper position in Figure 1. The charge has now been compressed between the annular ring or head 17 of the engine block and the closed lower end of the annular space 21, and when the pump has reached its upper position, the gas outlet port 43 of the pump piston registers with the orifice or opening 27, thus permitting the charge to be forced through the by-pass pipe 28 from the pump cylinder to the inlet ports 15-13 of the motor cylinder adjacent thereto. In this motor cylinder, the motor piston 30 is at the end of its downward stroke, and the charge therefore flows into the motor cylinder above the motor piston. The connections from these two adjacent pistons to the crank shaft are set at an angle of 180° and the pistons are therefore positioned at the top and bottom of their respective cylinders.

As the fresh charge enters the working cylinder above its piston 30, the gas is deflected upwardly by the baffle wall 44 on the top closed end of the piston, and caused to pass over the top of the exhaust or spent gas in the working cylinder, which exhaust gas, while the working cylinder is at its lower position, is being passed through the exhaust ports 14 and 16 to the exhaust manifold 45. The entrance of the fresh gas, under pressure assists in forcing out the spent gas through the exhaust ports and manifold, and preferably the exhaust port is opened slightly in advance of the opening of the intake or inlet port to the working cylinder above its piston. The volume and pressure of the intake gas is sufficient at all speeds of the engine to force out the burned gas, and

retain a supply of fresh gas in the cylinder for the subsequent combustion. The fresh gas is now compressed on the upstroke of the working piston, and is ignited or fired as the piston reaches nearly the end of its upstroke. 70

All air and gas locks are provided by the close fit of the several piston rings or packing rings on the periphery of the working and pump pistons, and the parts are so arranged that a packing ring is present at all 75 times between any gas pressure or vacuum or any port opening.

The pressure and volume of gas is regulated from the carburetor and the position of its throttle valve, thus controlling the 80 amount of fuel charge entering the mixing chamber of annular space 21, and in this manner the control of the fuel charge regulates the speed and power of the engines.

The fresh supply of gas flowing into the 85 space 21 is comparatively cool, and therefore absorbs heat from the pump piston and from the working piston and its cylinder. This absorption of heat prevents or reduces the extent of expansion of the pistons, which 90 would otherwise occur due to the heated condition thereof, and thus permits of a close fit of the working piston in its cylinder below the inlet and exhaust ports. The comparatively close fit of the lower part of the 95 working piston in its cylinder insures a uniform central movement of the piston, and at the same time obviates the necessity for a similar close fit of the upper part of the working piston in its cylinder. Therefore, 100 the comparatively loose-fitting upper end of the piston is permitted to expand under influence of the heat generated therein. This centering of the working piston also affects the pump piston, and relieves both the pistons and their cylinders of wear, thus prolonging the life of these parts and eliminating the chance for leaks due to imperfect fitting of the parts. 105

Claims:

1. The combination with the engine casing having a perforated head, of a working cylinder having an upper hollow stud projecting through said head and exterior securing means for said stud, an open supporting within the casing surrounding the working cylinder, a pump cylinder, and operative working and pump pistons in said cylinders. 115

2. The combination with the engine casing having an intermediate inner, open ring formed with an upper flange and a lower shoulder, of a cylinder fashioned with an exterior band engaging said ring and flange, and an angular flange on said band engaging 120 the lower edge of said ring, said casing having a perforated top, and a hollow stud on the cylinder projected through said perforated top, and exterior securing means for said stud. 125

3. The combination with the co-axial cylinders, of a working and pump piston formed as a rigid structure, the working cylinder comprising a tube closed at its upper end and open at its lower end, an engine casing having an interior, transverse supporting ring surrounding the working cylinder and forming a closed top for the pump cylinder, said pump cylinder encasing the lower por-

tion of the working cylinder to form an annular gas space, a duplicate engine structure, inlet and outlet ports as described, and bypass pipes connecting the pump cylinder of one engine with the working cylinder of the other engine for the purpose described. 10
